United States Patent Office

Des. 234,130
Patented Jan. 21, 1975

234,130

TRUCK

Edward S. Kress, 4009 N. Brookdale Place, and Ralph H.
Kress, 4444 Knoxville Ave., both of Peoria, Ill. 61614

Filed May 12, 1972, Ser. No. 252,712

Term of patent 14 years

Int. Cl. D12—08

U.S. Cl. D12—15

fig. 1a

fig. 1b

fig. 5

FIG. 1 is a perspective view of a truck showing our new design;

FIG. 2 is a front elevation view thereof, with portions of the rear tires being omitted for ease of illustration;

FIG. 3 is a right side elevational view thereof;

FIG. 4 is a top plan view thereof; and

FIG. 5 is a rear elevational view thereof, with portions of the front tires being omitted for ease of illustration.

We claim:

The ornamental design for a truck, as shown and described.
